UNITED STATES PATENT OFFICE

PAUL HEGYES, OF BROOKLYN, AND JOSEF ROSENFELD, OF NEW YORK, N. Y.

SELECTIVE DISCHARGE FAUCET

Application filed October 15, 1928. Serial No. 312,525.

This invention relates to a selective discharge faucet, and its object is to provide an article of this character; which, by the manipulation of a single lever may be made to release any one of a variety of syrups or other liquids.

A further object is a form of construction which is of neat and ornamental appearance and which may be easily taken apart for 10 cleaning.

These and other objects and features of the invention will be fully described in the following specification and illustrated in the accompanying drawings, in which:

15 Fig. 1 shows a side view of the device; portions being broken away to disclose the working parts.

Fig. 2 shows a fragmentary section on the line 2—2 of Figure 1.

20 Fig. 3 shows a front view of the upper portion of the cylinder casing.

Fig. 4 shows a cross section on the line 4—4 of Figure 1.

The device may be of any suitable material and plated or otherwise finished as required.

The construction is as follows: Referring chiefly to Figure 1 of the drawings; a block, or base element 10 is provided with a plurality of holes, or tubes 11, 12, 13 etc. and these are arranged in vertical rows on opposite sides of the said block. They are threaded as shown at 14, 15 etc. so that pipes may be easily attached thus connecting the faucet 35 with the various syrups, or liquids which it is desired to dispense. Preferably the faucet is mounted on a suitable tank which is divided into separate compartments; it may, however, be applied in other ways.

40 A hole 16 passes vertically through the block, and the tubes 11, 12, 13 etc. open into it as indicated by the dotted lines in Figure 2.

A vertical cylinder 20 is attached to the block as seen in Figure 1 and has a closure 45 lid 21 at its upper extremity. A longitudi-

nally slidable and rotatable nozzle element 22 fits smoothly within the hole 16 and may be turned, or raised, or lowered by the lever 23 which is secured to the top shoulder 24; this shoulder being integral with the said nozzle 50 element.

A spring 25 bears against the block element at the bottom and the shoulder 24 at the top and serves to raise or retract the nozzle element when the lever is in its central position 55 of alignment.

A nozzle hole 26 is turned backward at its upper or rear end and assumes the position indicated at 27 when the faucet is closed. It is obvious that when the lever is turned to 60 the right or left, this hole will connect with one of the pipe holes.

To connect with the middle hole 12 in one of the rows of holes or the one opposite thereto; the lever is thrown, first into line with the slot 28—see Figure 3—and is then pushed downward into the middle cross slot and turned to engage in the end 29 of said slot or in the opposite end 30 of the slot. Similar movements will connect the nozzle hole with 70 either of the lower holes in the block.

It will thus be seen that a simple movement of the lever 23 will permit the drawing off of any of the liquids or syrups at will and with the utmost speed and efficiency.

75 While we have shown the device in its preferred form of construction; it is understood that such minor changes of detail may be made therein as may come within the spirit and scope of the appended claim.

Having thus described our invention, what we claim as new and desire to secure by Letters Patent, is as follows:

In an article of the class described, a base element having longitudinal holes therein arranged in vertical rows, a rotatable and longitudinally slidable nozzle element mounted transversely in conjunction with the said base element, a discharge hole in the said nozzle element having a rearwardly disposed open- 85 90

ing adapted to be swung into line with any one of the holes of the base element, a vertical casing about the said nozzle element, a retracting spring therein, a lever affixed to the said nozzle element and a series of superposed transverse stop slots in said casing adapted to receive the shank of the said lever.

Signed at New York, in the county of New York and State of New York, this 22nd day of September, A. D. 1928.

PAUL HEGYES.
JOSEF ROSENFELD.
